UNITED STATES PATENT OFFICE

ALBERT J. BATES, OF CHICAGO, ILLINOIS.

RAILWAY-TIE.

1,042,071.

Specification of Letters Patent.

Patented Oct. 22, 1912.

Application filed August 25, 1911. Serial No. 645,896.

To all whom it may concern:

Be it known that I, ALBERT J. BATES, a citizen of the United States, residing at Chicago, in the county of Cook and State 5 of Illinois, have invented certain new and useful Improvements in Railway-Ties, of which the following is a specification.

This invention relates to railway ties and particularly to the class of composition ties 10 as distinguished from those made entirely of wood or metal.

The primary object of the invention is to provide a composition tie of simple and inexpensive construction which has the necessary and desired degree of flexibility and elasticity and can be readily substituted for the ordinary wood tie.

One of the serious difficulties encountered in establishing and maintaining proper 20 roadbeds is to prevent the unequal distribution of pressure on the ties. As the greater portion of a wood tie is located between the rails, the pressure per square inch on the tie is consequently less between the rails 25 than outside the rails and the result is that when pressure is applied to the rails the outer ends of the ties are depressed while the center of the tie is held up. Thus the tie becomes "center-bound" and the effect 30 of this is to cause a railroad train moving over the rails to be pulled up hill to the extent of the weight and power necessary to bend the ties to their established base. To prevent this bending action requires constant 35 attention on the part of the section men on the road as it is necessary for them to watch the ties carefully and keep them filled and tamped under the outer ends.

My invention overcomes this difficulty by 40 providing a tie comprising a pedestal for each rail arranged to receive and support the rail at its center. This arrangement provides for a uniform distribution of the load on the base of the pedestal and consequently whatever settling of the pedestal 45 takes place in service is necessarily uniform throughout the area of the pedestal, thereby improving the foundation for the pedestal and wholly avoiding the necessity for filling 50 and tamping now incident to the use of wood and metal ties.

Another important object of the invention is to provide a railway tie comprising pedestals spaced apart for supporting the rails 55 and made of a plastic material, such as concrete, reinforced and connected by a trussed

metal structure in such a manner that the pedestals will resist not only the compression strains but also the tension strains to which they are subjected in service.

Further objects of the invention are to provide a composition tie which will have sufficient elasticity and flexibility to properly adjust itself under the load carried by the rails and at the same time distribute the load evenly and uniformly throughout the pedestals supporting the rails; to reinforce the pedestals in a simple and efficient manner to prevent them from breaking when under load; and is to reduce the cost of maintenance of a roadbed by providing an efficient substitute for wood which will have a much longer life in service than a wood tie and which will avoid the unequal distribution of the load which produces center-bound ties and overcomes other objections to wood ties.

In the accompanying drawings illustrating a preferred embodiment of the invention, Figure 1 is a plan view of tie showing the rails in place thereon; Fig. 2 is a side elevation of the tie showing the rails in section; Fig. 3 is an enlarged longitudinal sectional view through one of the pedestals of the tie and the rail; Fig. 4 is a transverse sectional view on the line 4-4 of Fig. 3; Fig. 5 is a detail sectional view showing the rail on the tie in a position to increase the track gage, on a curve for example; Fig. 6 shows one end of the trussed metal structure with the longitudinal truss rods and the transverse rods in position thereon, the latter being in section; Fig. 7 is a transverse view on a line indicated by 7-7, Fig. 6, and showing the metal portion of the tie; Fig. 8 is a perspective view of one of the wear plates; Fig. 9 is a perspective view of an anchor plate, and Figs. 10, 11 and 12 are perspective views of transverse rods and a wedge block respectively.

Referring to the drawings in which letters of reference indicate corresponding parts of the several figures, A, A, designate the two pedestals of the tie which are spaced apart to occupy a position centrally disposed below the track rails B. These pedestals are constructed alike and each is preferably made of a plastic composition such as concrete reinforced and connected, as hereinafter more specifically set forth, by the trussed metal reinforcing structures C, C, which are preferably embedded in the

pedestals and extend approximately throughout their length.

The trussed metal structure which I prefer to employ for reinforcing and connecting the pedestals is fully set forth in my allowed applications Serial No. 556,221, filed April 18, 1910, and Serial No. 583,394, filed September 23rd, 1910, and comprises a one-piece triangulated article of ductile metal 10 consisting of two side members *c*, *c*, and a zig-zag intermediate member *c'*, forming with the side members a series of integral truss elements of triangular form. I prefer to employ a pair of these trussed reinforces, 15 *C*, *C*, substantially the length of the tie, and arrange them in parallel relation, spaced apart, and embed them in the concrete pedestals, the concrete preferably entirely covering that portion of each reinforce embedded therein. This form of reinforce, 20 when combined with the concrete, provides a pedestal of strong and substantial character which combines the compression resisting strains of the concrete with the tension resisting strains of the reinforce in a 25 simple, permanent and serviceable manner.

For the purpose of greater strength I may employ, in addition to the trussed metal reinforce, transverse rods *D* and longitudinal 30 truss rods *E* in each pedestal. The transverse rods have bent ends *d* to engage the trussed reinforces, and the longitudinal truss rods are anchored at their ends to two of the transverse rods *D'* on the top of the trussed 35 reinforces and engage one of the transverse rods *D''* at the bottom of the trussed reinforces. The transverse rods which are engaged by the longitudinal truss rods are preferably bent as indicated by the trans- 40 verse truss rod *D''* in Fig. 7.

The trussed structures, transverse rods and longitudinal truss rods form a skeleton box or cage-like frame within which the major part of the concrete pedestal is 45 closed. The trussed structures are preferably located adjacent the sides of the pedestals and are engaged at or about the top and the bottom thereof by the transverse rods, and the truss rods are located between the 50 trussed structures and extend approximately throughout the length of the pedestal in 55 reversely inclined directions from the center of the pedestal. This construction provides a substantial and compact concrete pedestal, strongly reinforced so as to prevent the pedestal from splitting longitudinally and also to prevent the concrete from crumbling or breaking away from the reinforces without first changing or destroying these reinforces.

60 that is to say, without changing the length of one of the members of one or more of the triangles of which each reinforce is composed. The principal strains to which a railway tie is subjected are tension strains at 65 the bottom of the tie and compression strains

at the top of the tie due to the tendency of the tie to bend under the pressure of the load on the rails, and the trussed metal reinforces embedded side by side in the pedestals and connecting the pedestals serve not only to effectively resist these tension strains but they also confine and hold the concrete so that it will resist any tendency to split or break down or crumble, and will be maintained in a solid compact condition. 70

A wear plate *F* is embedded and permanently anchored in each pedestal to form a seat for the rail and this wear plate is provided with lips or projections *f*, which are stamped out of the plate to make locking 75 engagement with the concrete of the pedestal. At the sides of the wear plate I provide openings *G* for the holders *H* and these openings are preferably made by stamping and bending lugs *g* downwardly in parallel 80 relation to assist in anchoring the plate to pedestal. 85

The holder *H* is substantially similar to the ordinary railway spike except that it is provided with a hooked end *h*, to engage the 90 head *i*, on the anchor plate *I*, which is embedded in the concrete pedestal beneath the wear plate. These holders are arranged in openings *J* on each side of the wear plate and these openings preferably extend entirely through the pedestals for drainage 95 and have inclined side walls *j*. The holders are secured in proper position by wood keys *K* which are driven into the openings *J*, alongside of the holders until the upper end 100 of the key is engaged beneath the head *h* forming part of the head of the holder. Thus the keys are securely held in place by the holders while they in turn secure the 105 holders in their proper position, the flange *h''*, forming part of the head of the holder being engaged with the flange of the rail and the hook *h* being engaged with the head *i* of the anchor plate.

For ordinary purposes the rail will be located centrally above the anchor plate and the keys *K* employed for securing the holders *H* will be of uniform size to properly position the tie and rail relative to each other, but if it should be desired to increase 110 the gage of the track, on curves for example, this can be readily accomplished without changing the tie by simply providing keys of unequal size, as indicated in Fig. 5, which shows the rail shifted to one side of the center of the wear plate and the pedestal. By varying the size of the keys *K*, the position of the rail relative to the pedestal may be 115 changed as desired.

My invention provides a substitute for the 120 ordinary wood tie in common use which not only possesses all of the advantages of a wood tie but overcomes many of its disadvantages and also greatly increases the life 125 of the tie. As I have before stated, one dis- 130

advantage of the use of wood ties is the constant tendency to depress the ends under the pressure of the load carried by the rail until they become center-bound, that is, raised at the center and depressed at the ends, and section men are constantly employed in tamping the ends of the ties to lift them up to the proper grade. This center-bound action of the tie is due to the fact that the maximum area of the tie is between the rails and consequently the pressure per square inch on the tie is less between the rails than outside of the rails. My invention overcomes this trouble by providing two pedestals of approximately the same size and spaced apart to support the rails centrally disposed thereon, so that there is as much of the pedestal on one side of the rail as on the other, and consequently there is no opportunity for the tie to become center-bound.

The concrete pedestal reinforced with the trussed metal structure, as shown and described, forms a solid and substantial foundation for the rail, combining the pressure resisting qualities of the concrete with the tension resisting qualities of the trussed reinforce, and the load carried by each rail centrally positioned on the pedestal will be distributed evenly and uniformly over the entire base of the pedestal. The pedestals are permanently connected together by the truss reinforces which provide the necessary amount of elasticity and flexibility between the pedestals to permit them to adjust themselves relatively and independently as the conditions of service may require.

Besides the other advantages of my invention hereinbefore noted it will be readily understood that cross ties of standard size may be employed for rails of different sizes by simply employing wood keys of the right size to secure the rails in place. The metallic parts of the means for fastening the rail to the tie are separated entirely from the reinforce metallic parts embedded in the pedestals so that the rails will be properly insulated from each other.

I do not claim in this application the fastening features except as they are used in combination with the trussed metal structures, for these features are separately claimed in my divisional application Serial No. 664,544 filed December 8, 1911.

I claim:

1. A railway tie comprising a pair of rail supporting pedestals made of a plastic material and separated from each other, and a pair of one-piece trussed metal structures of skeleton form made of ductile metal embedded in said pedestals adjacent to the sides thereof to reinforce and connect the same, substantially as described.

2. A railway tie comprising a pair of pedestals made of plastic material separated from each other to support the rails, and a

pair of one-piece trussed metal structures of skeleton form made of ductile metal embedded in said pedestals adjacent to the sides thereof and extending substantially throughout their length to reinforce and connect the same, substantially as described.

3. A railway tie comprising a pair of pedestals made of plastic material and separated from each other to support the rails, and a pair of one-piece trussed metal structures of skeleton form embedded in said pedestals adjacent to the sides thereof and forming a connection therebetween, substantially as described.

4. A railway tie comprising a pair of pedestals made of plastic material and spaced apart to support the rails in the center of the length of the pedestals, and a pair of one-piece trussed metal structures of skeleton form embedded in said pedestals adjacent to the sides thereof to reinforce and connect the same, substantially as described.

5. A railway tie comprising a pair of pedestals made of plastic material and spaced apart to support the rails, a skeleton box-like frame embedded in each pedestal adjacent to the surface thereof, and a pair of parallel one-piece trussed metal structures of skeleton form forming parts of said frames and reinforcing and connecting the pedestals, substantially as described.

6. A railway tie comprising a pair of pedestals made of plastic material and separated from each other to support the rails, a pair of one-piece trussed metal structures of skeleton form embedded in said pedestals adjacent to the sides thereof to reinforce and connect the same, and transverse bars engaging the trussed structures and embedded in said pedestals, substantially as described.

7. A railway tie comprising a pair of pedestals made of plastic material separated from each other to support the rails, a pair of trussed metal structures embedded in said pedestals adjacent to the sides thereof and substantially throughout their length to reinforce and connect the same, and longitudinally extending truss rods connected with said trussed structures and embedded in said pedestals, substantially as described.

8. A railway tie comprising a pair of pedestals made of plastic material and spaced apart to support the rails, a pair of parallel trussed metal structures embedded in said pedestals adjacent to the sides thereof to reinforce and connect the same, and longitudinally extending truss rods located between said trussed structures and connected therewith and embedded in said pedestals, substantially as described.

9. A railway tie comprising a pair of pedestals made of plastic material and spaced apart to support the rails, a pair of parallel trussed metal structures embedded

in said pedestals adjacent to the sides thereof to reinforce and connect the same, transverse bars engaging the trussed structures and embedded in said pedestals; and longitudinally extending truss rods connected with said trussed structures and embedded in said pedestals, substantially as described.

10. A railway tie comprising a pair of pedestals made of plastic material and spaced apart to support the rails, a pair of parallel trussed metal structures embedded in said pedestals adjacent to the sides thereof to reinforce and connect the same, transverse bars engaging the trussed structures and embedded in said pedestals, and longitudinally extending truss rods located between said trussed structures and engaged with some of said transverse bars and embedded in said pedestals, substantially as described.

11. A railway tie comprising a pair of pedestals made of plastic material and spaced apart to support the rails, a pair of one-piece trussed metal structures of skeleton form embedded in said pedestals adjacent to the sides thereof to reinforce and connect the same, and bars embedded in each pedestal and engaged with the trussed structures to form therewith a skeleton box-like frame in each pedestal, substantially as described.

12. A railway tie comprising a pedestal made of plastic material and having openings extending entirely therethrough, opposite walls of each of said openings being inclined, and a metal wear plate permanently anchored in said pedestal between said openings to engage the rail, substantially as described.

13. A railway tie comprising a pair of pedestals made of plastic material and separated from each other to support the rails, a pair of one-piece trussed metal structures of skeleton form embedded in said pedestals and forming a connection therebetween, and means for fastening the rails to the pedestals, said fastening means and trussed metal structures being separated from each other to insulate the rails from each other, substantially as described.

14. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings to receive the rail fastening means and extending entirely through the tie and having inclined outer walls, substantially as described.

15. A railway tie comprising a pair of pedestals made of plastic material and separated from each other to support the rails, a pair of one-piece trussed metal structures

of skeleton form embedded in said pedestals adjacent to the sides thereof and forming a connection therebetween, each of said pedestals having openings to receive the rail fastening means and extending entirely through the tie and having inclined inner walls adjacent to the rail, substantially as described.

16. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings to receive the rail fastening means and provided with inclined outer and inner walls, substantially as described.

17. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings to receive the rail fastening means and extending entirely through the tie, the outer wall of each opening being inclined downwardly and inwardly and the upper portion of the inner wall of each opening being inclined downwardly and outwardly, substantially as described.

18. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings to receive the rail fastening means and extending entirely through the tie, the upper portion of the section of the tie located between said openings having its side walls extending outwardly beyond the side walls of the lower portion of said section, substantially as described.

19. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings for the rail fastening means, the lower portion of the section of the tie between said openings being of less width than the upper portion and said upper portion having downwardly and outwardly inclined side walls projecting outwardly beyond the side walls of the lower portion of said section, substantially as described.

20. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings for the rail fastening means, an anchor plate embedded in the pedestals and projecting into said openings, and upwardly removable holders detachably engaged with the ends of said anchor plate in said openings and with the flange of the rail, substantially as described.
21. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings for the rail fastening means, an anchor plate embedded in the pedestals and having ribs located in said openings, and upwardly removable holders detachably engaged with said ribs and with the flange of the rail, substantially as described.
22. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings for the rail fastening means, an anchor plate embedded in the pedestal and projecting into said openings, the outer walls of said openings being inclined downwardly and inwardly and the inner walls of said openings being inclined downwardly and outwardly above the anchor plate, substantially as described.
23. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings for the rail fastening means, an anchor plate embedded in the tie and having ribs on its underside and at its outer edges, the section of the tie below said anchor plate being of less width than the width of the anchor plate to leave said ribs exposed in said opening, substantially as described.
24. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings with inclined outer walls, an anchor plate embedded in the pedestal and projecting into said openings, upwardly removable holders detachably engaged with said anchor plate and the flange of the rail, and wedge keys driven in said openings alongside the holders to hold them in place, substantially as described.
25. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings therein, upwardly removable holders arranged in said openings and detachably engaged with the pedestal at their lower ends and with the rail flange at their upper ends, and wedge keys arranged in said openings to hold the holders in place, said keys being held in place by the holders, substantially as described.
26. A railway tie comprising a pair of pedestals made of plastic material and separated from each other to support the rails, a pair of one-piece trussed metal structures of skeleton form embedded in said pedestals adjacent to the sides thereof and forming a connection therebetween, each of said pedestals having openings therein, anchor devices in said openings, upwardly removable holders detachably engaged with the flange of the rail and having hooked ends engaged with said anchor devices, and wedge keys driven in the openings alongside of said holders to hold them in said engagement, substantially as described.
